UNITED STATES PATENT OFFICE.

SAMUEL C. LAY, OF RIDGEVILLE, INDIANA, AND FREDERICK M. BAKER, OF DETROIT, MICHIGAN; SAID BAKER ASSIGNOR TO THE JOSEPH LAY COMPANY, OF RIDGEVILLE, INDIANA, A CORPORATION.

BROOM-STAPLING MACHINE.

1,279,885.

Specification of Letters Patent. Patented Sept. 24, 1918.

Application filed February 12, 1917. Serial No. 148,132.

To all whom it may concern:

Be it known that we, SAMUEL C. LAY and FREDERICK M. BAKER, citizens of the United States, and residents of Ridgeville and Detroit, respectively, counties of Randolph and Wayne, respectively and States of Indiana and Michigan, respectively, have invented a certain new and useful Broom-Stapling Machine; and we do hereby declare that the following is a full, clear, and exact description thereof, reference being had to the accompanying drawings, in which like letters refer to like parts.

The object of this invention is to provide a broom stapling machine of as simple construction as possible which will properly cut the staples, form them and drive them through the metal casing of the broom head and clench them therein in the proper manner.

Another feature of the invention consists of the means for cutting the wire into the proper length to form a staple, said means being arranged so as to give the desired bevel to the ends of the staple so as to provide points thereon for piercing the metal casing and broom straw, and to give the ends the desired clench after being driven therein.

A further feature is the construction of the staple forming mechanism and the driving mechanism whereby the staple will be disengaged from the staple former so as to avoid it when being driven into the broom head, thus doing away with the complicated mechanism usually employed in providing a disappearing staple former.

Still another feature of the invention is the means for elevating the broom table so as to raise the broom head in position to engage the staple driving mechanism. The broom may be freely positioned by the operator when not being stapled, and when in proper position for the staples, each staple will be driven and clenched instantaneously.

The full nature of the invention will be understood from the accompanying drawings and the following description and claims.

Figure 1 is a front elevation of the broom stapling machine. Fig. 2 is a side elevation thereof. Fig. 3 is a central vertical section on the line 3—3 of Fig. 1, showing the wire in position to be formed. Fig. 4 is the same as Fig. 3 showing the mechanism

after having formed the staple. Fig. 5 shows the lower portion of Fig. 4 with the staple in position to be driven. Fig. 6 is an enlarged view of the wire feeding mechanism. Fig. 7 is a cross section on the line 7—7 of Fig. 6. Fig. 8 is an elevation of the wire gripping mechanism. Fig. 9 is the side elevation of the lower portion of the machine showing the broom table in elevated position. Fig. 10 is a horizontal cross section on the line 10—10 of Fig. 6.

There is shown in the drawings a staple forming machine having a supporting base 10 with an upright frame 11 secured thereon. On the upper portion of the frame 11 there are bearings 12 through which a shaft 13 extends, said shaft being connected at one end thereof to driving wheel 14 through a clutch mechanism 15 of the ordinary construction, which need not be described herein, through which the driving wheel 14 is thrown into and out of operation with the shaft 13. At the lower part of the machine is a foot lever 16 secured to a shaft 17 on which there is secured a lever 18 extending within the base 10. Pivoted to the end of the lever 18 there is a rod 19 which is connected at its other end to the clutch mechanism 15 for operating said clutch whereby the operation of the machine may be controlled.

Secured on the shaft 13 there is a gear 20 which drives a chain 21 which passes around an idler gear 23 and engages and drives the gear 22 on the shaft 26, and the gear 24 on the shaft 25, the chain then returns directly to the gear 20. On the shaft 26 there is a gear 27 which meshes with and drives the gear 28 on the shaft 29. The shaft 26 passes through the frame of the machine and drives a feeding roll 30 which is secured thereon and the shaft 29 drives the feeding roll 31 in the opposite direction. The end of the shaft 29 on which the roll 31 is secured is mounted in a bearing 32 which is slidably mounted in the frame, and adjusted by the tension of the spring 35 so as to cause the roll 31 to engage the roll 30, said spring being adjusted by the screw 33 mounted in the housing 34. The feeding rolls 30 and 31 are provided with annular grooves 36 through which the staple wire 37 extends. It must, therefore, be understood that when the feeding rolls engage each other the staple wire is

fed into the stapling mechanism, which will be hereinafter described. On the feeding roll 30 there is a cam portion 38 which extends partly around said roll and which will 5 engage the roll 31 when the rolls are turned, so as to force the roll 31 upwardly in its sliding bearing 32 whereby the wire will be disengaged and will not be fed into the stapling mechanism until the cam portion 10 permits the roll 31 to reengage the roll 30 and continue to feed in the wire. It will, therefore, be seen that the wire will be fed into the machine at given intervals and in given lengths depending upon the size of 15 the cam. For preventing the further movement of the wire after it is released from the rolls there is provided a clenching device 39 through which the wire must pass before entering the rolls, which frictionally engages 20 the wire and retains it until the pressure of the rolls overcomes the friction and forces it into the machine. The wire is gripped in the jaw of the device by the tension of the spring 40 which tends to cause the jaw to 25 frictionally engage the wire, as shown in Figs. 6 and 8.

The staple forming mechanism is driven by a cam 41 keyed to the opposite end of the shaft 13 from the gear 20. Said cam is 30 adapted to engage the roller 42 on the plunger 43. Said plunger is adapted to reciprocate in a housing 44 in which there is a compression spring 45 which engages said plunger for returning it to its normal position 35 after having been operated by said cam. On the lower end of the plunger there is a shaft 46 which extends downwardly through the compression spring and housing and has on the end thereof a head 47, said head being 40 in position to engage the staple forming lever 48 when the plunger is operated. The head 47 rides in a T-slot in the projection 84, which is secured to the lever 48.

Pivoted mounted on the cam 41 by the 45 pin 49 there is a connecting rod 50 which is connected to the hammer 51 by the wrist pin 52. Said hammer is adapted to reciprocate in the bearing 53.

Keyed on the shaft 13 there is a cam 54 50 which is provided with a brake drum adapted to be engaged by the brake band 55 so that the shaft 13 will stop immediately upon being released from the driving wheel 14 by the clutch mechanism. The cam 54 is in 55 position to engage a roller 56 on one end of a lever 57 which is pivoted to the frame at 58, the other end of the lever extending through a slot in the end of the staple forming lever 48 so as to engage said lever for 60 forcing it forwardly on its pivot pin 59. The end of the lever 48 is yieldingly secured to the frame by the spring 60 which will return said lever 48 after having been operated by the lever 57. The staple forming 65 end of the lever 48 is provided with a slot

which will straddle the staple forming block 61, said lever being provided with a groove 62 on the inner side thereof. The staple wire is adapted to be inserted between the lever 48 and the staple forming block when 70 it is in the position shown in Fig. 3. The lever 48 is then engaged by the head 47 and forced down over the block 61 at the same time cutting the wire by the knife edge 63 secured to one side of the lever 48, as shown 75 in Fig. 6. The wire is formed in the groove 62 around the block 61 in the form of a staple with its beveled or pointed ends extending downwardly. The cam 54 then engages the lever 57 which forces the lever 48 80 forward so that the staple is disengaged from the block 61 and remains in the groove 62 of the lever 48 by the tension of the wire in a position shown in Fig. 5. When the machine is in this position the staple is cut 85 and formed and ready to be driven into the broom head.

Pivoted to the base of the machine there is a lever 70 having a pin 71 therein adapted to engage the slot 72 in the drum 73 which is 90 secured on the shaft 25. The upper end of the lever 70 is secured to a rod 74 which is pivoted at its other end to the sliding frame 75. The lower end of said frame is curved and adapted to slidably engage the extensions 76 which have upwardly curved surfaces 77. Pivoted to the upper portion of the frame 75 there is a broom table 78 which is slidably supported on the frame 79 so that when the frame 75 is forced forward 95 by means of the rod 74 it will engage the upwardly curved surface and force the broom table in an upper position as shown in Fig. 9, and when released the table will drop down to the position shown in Fig. 2, in 100 which position a broom may be placed thereon and adjusted to the position in which the staple is to be inserted, and then lifted upwardly against the stapling mechanism by said frame when it is ready to be 105 stapled.

Secured in the hammer 51 by means of the set screws 80 there is an extension 81 to the hammer, and adjustable therein, which extension is adapted to be driven through the 110 slot in the staple forming lever 48 so as to engage the staple and drive it into the broom cap.

The operation of the machine is as follows:

A broom head 82 is placed on the table 78 when in its lowered position as shown in Fig. 2. When properly adjusted to receive the staple the operator throws the clutch mechanism into engagement by the foot lever and the feed rolls engage the wire and feed it in position to be cut into the proper length for a staple. The cam 41 then engages the roller 42 and forces the staple forming lever 48 down over the wire and 125 130

staple forming block so that a staple is formed within the slot 62. The lever 57 is then engaged by the cam 54 so as to force the staple forming lever outwardly to dis- 5 engage the block and retain the staple by means of its spring tension in position shown in Fig. 5. The broom table is then forced in its upper position as shown in Fig. 9 and the hammer 51 causes the staple to be driven 10 into the broom head by means of extension 81 through the staple guide 83 against which the broom is forced by the broom table 78. While the operation of driving the staple into the broom is going on the staple forming 15 lever 48 is moved inwardly by means of the spring 60 out of the way of the driving extension 81 and is drawn upward out of engagement with the block 61 by means of the head 47 engaging the projection 84, as 20 shown in Fig. 3. The continued operation of the machine brings a new length of staple wire in position to be engaged by the staple forming block preparatory to another operation.

25 The invention claimed is:

1. In a stapling machine, a wire feeding mechanism, a stationary staple forming block, a lever adapted to form a staple, means for forcing said lever upon said block, means independent of the lever forcing means for moving the lever endwise to place the staple in position to be driven, a staple driving mechanism, and means independent of the lever forcing and the lever 30 moving mechanism for operating said staple driving mechanism.

2. In a stapling machine, a wire feeding mechanism, a stationary staple forming block, a staple forming lever slidably pivoted in said machine, means for forcing said lever upon said block to form a staple, means independent of the lever lowering device for engaging and moving said lever endwise and causing it to remove the staple 40 from said block and hold it in position to be driven, and means independent of the lever lowering and lever moving device for driving said staple after it has been formed.

3. In a staple forming machine, a wire 45 feeding mechanism, a stationary staple forming block, a staple forming lever slidably pivoted in said machine adapted to form a staple on said block, means for engaging said lever and causing it to remove the staple from said block, means on said lever for holding said staple, means independent of the lever engaging means for forcing one end of said staple forming lever downwardly, and means independent of 55 the lever engaging and lever lowering means for driving said staple after it has been formed.

4. In a stapling machine, a wire feeding mechanism, a stationary staple forming block, a pivotally mounted staple former,

means to lower one end of said former and form a staple on said block, a knife on said staple former for cutting said wire and beveling the ends thereof, means independent of the staple former lowering means for moving said staple former endwise to remove said staple from said block, means for operating said feeding mechanism and staple former, and means independent of the staple former lowering means and staple former 70 moving means for driving said staple after it has been formed.

5. In a staple forming machine including a wire feeding mechanism, a stationary staple forming block, a horizontally disposed staple former adapted to form a staple on said block, and then move it in position to be driven, means for driving said staple after it has been formed, a plunger having 80 a head thereon for engaging and forcing said staple former over said block, means for returning said plunger to position after being operated, and means on said machine for driving said plunger.

6. In a staple forming machine including a wire feeding mechanism, a stationary staple forming block, a horizontal staple former adapted to form a staple on said block and hold it in position to be driven, means for driving said staple after it has 90 been formed, a plunger having a head thereon for engaging and operating said staple former, a spring for returning said plunger to its normal position after being operated, and a cam driven by said machine adapted 95 to engage and drive said plunger.

7. In a stapling machine including a driving shaft, cam operated wire feeding rolls, means on said shaft for driving said rolls, a stationary staple forming block, a staple 100 forming lever adapted to engage and form a staple on said block, means for causing said lever to disengage the staple from said block, means for operating said lever to form the staple, a work table, means for elevating said work table to bring the work 105 into proper position to be stapled, and a hammer for engaging and driving the staple into said work.

8. In a stapling machine including a driving shaft, cam operated wire feeding rolls, means on said shaft for driving said rolls, a stationary staple forming block, a staple forming lever adapted to engage and form a staple on said block, means for causing 110 said lever to disengage the staple from said block, means for operating said lever to form the staple, a work table, means for elevating said work table to bring the work 115 into proper position to be stapled, and a hammer for engaging and driving the staple into said work, said staple forming lever being so constructed as to retain the staple 120 in position to be driven.

9. In a stapling machine including a driv-

ing shaft, cam operated wire feeding rolls, means on said shaft for driving said rolls, a stationary staple forming block, a staple forming lever adapted to engage and form 5 a staple on said block, means for causing said lever to disengage the staple from said block, means for operating said lever to form the staple, a work table, means for elevating said work table to bring the work into 10 proper position to be stapled, a hammer for engaging and driving the staple into said work, and cam operated means on said shaft for driving said hammer.

10. In a stapling machine including a 15 driving shaft, cam operated wire feeding rolls, means on said shaft for driving said rolls, a stationary staple forming block, a staple forming lever adapted to engage and form a staple on said block, means for causing 20 said lever to disengage the staple from said block, means for operating said lever to form the staple, a work table, means for elevating said work table to bring the work into proper position to be stapled, a hammer 25 for engaging and driving the staple into said work, and means for clenching the staple in said work when being driven therein.

11. In a stapling machine including a driving shaft, cam operated wire feeding 30 rolls, means on said shaft for driving said rolls, a stationary staple forming block, a staple forming lever adapted to engage and form a staple on said block, means for causing 35 said lever to disengage the staple from said block, a cam on said shaft for engaging and operating said lever disengaging means, means on said staple forming lever for retaining the staple in position to be driven, a plunger for operating said lever, 40 a cam on said shaft for operating and engaging said plunger, means for returning 45 said staple forming lever to position after being operated, a work table for elevating the work in position to be stapled, a hammer for engaging and driving said staple into the work, and means for operating said hammer.

In witness whereof, we have hereunto affixed our signatures in the presence of the 50 witnesses herein named.

SAMUEL C. LAY.

FREDERICK M. BAKER.
